UNITED STATES PATENT OFFICE.

LUCY B. PHILLIPS, OF BRIDGETON, NEW JERSEY, EXECUTRIX OF WILLIAM H. PHILLIPS, DECEASED.

AIR-CUSHION.

SPECIFICATION forming part of Letters Patent No. 716,752, dated December 23, 1902.

Application filed January 9, 1902. Serial No. 89,088. (No model.)

To all whom it may concern:

Be it known that I, LUCY B. PHILLIPS, a citizen of the United States, residing at Bridgeton, in the county of Cumberland and State 5 of New Jersey, executrix of the estate of WILLIAM H. PHILLIPS, late a citizen of the United States, residing at Bridgeton, in the county of Cumberland and State of New Jersey, deceased, (as by reference to the duly-certified copy of letters testament hereto annexed will more fully appear,) do hereby declare that WILLIAM H. PHILLIPS invented a new and useful Air-Cushion, of which the following is a specification.

15 This invention relates to air-cushions adapted to be applied to various uses.

The object of the invention is to provide a cushion composed of sections, which are so connected as to avoid contact of the person

20 using them with the connecting means.

Figure 1 of the accompanying drawings represents a bottom plan view of two cushion-sections, showing this improved method of connecting them. Fig. 2 represents an end 25 elevation thereof.

The same reference-numerals indicate corresponding parts in both figures.

In the form illustrated in Figs. 1 and 2 two cushion-sections 10 and 20 are shown provided with flaps 11 and 21, extending along the bottoms thereof near their inner edges, and these flaps are provided with longitudinally-aligned perforations, as 12 and 22. A suitable lacing-cord 30 is threaded through

35 the perforations, as 12 and 22, in the usual manner and the ends thereof tied together in a bow-knot or connected in any desired manner, said cord operating to hold the cushion-sections in parallelism and against separation

40 under imposed weight. The cushion-sections are preferably provided with loops or tabs, as 13 and 23, which may be attached to the cushions at any desired point, preferably the corners, and are adapted to be used as fastening means for attaching the cushion to the

45 bed, chair, or other article to which it is desired to attach it. These connecting devices do not extend the entire length of the sections, but terminate at a point near the opposite ends thereof, whereby all possibility of

50 the connecting device coming into contact with the body of the person is avoided, for if

the connecting-web or the lacing were carried to the extreme ends of the cushion-sections it would follow the curve of the back 55 and come so high as to touch and annoy the patient, while the said cushion-sections being connected for the greater part of their length are prevented from separating too far apart when the patient's weight is applied on the 60 tops thereof. More perfect ventilation is provided, as the cushion-sections are separated throughout their entire length, and free circulation of air permitted. Each section is preferably provided with a nipple-valve 14 65 and 24 at one of the outer corners thereof, thereby permitting ready access to the sections for the purpose of inflation or deflation without disturbing the patient upon the cushion and permitting equal or unequal inflation, 70 as may be desired.

The principal point of importance in this invention lies in the point of attachment of the connecting flaps or web to the bottom of the cushion-sections, which gives all the 75 depth possible to be obtained, as the connecting means lies flat on the bed, and the height of the surface upon which the patient lies may be regulated at will by the degree of inflation of the cushion-sections.

70 The lacing allows the two sections to be disconnected completely for use as single pillows or pads, permits replacement of one part of the cushion in case of injury without affecting the other part, and allows adjustment 85 of the sections at various distances apart to accommodate different patients.

80 What is claimed is—

An air-cushion comprising two rectangular pillow-shaped sections, a flap secured to the 90 under side of each section and extending parallel with one edge thereof, and a lacing associated with the flaps for holding the sections parallel in use.

In testimony that I claim the foregoing as 95 the invention of WILLIAM H. PHILLIPS I have hereto affixed my signature in the presence of two witnesses.

LUCY B. PHILLIPS,
Executrix of the estate of William H. Phillips,
deceased.
